UNITED STATES PATENT OFFICE.

FREDERIK G. WHITTINGTON, OF EVANSTON, ILLINOIS, ASSIGNOR TO STEWART-WARNER SPEEDOMETER CORPORATION, OF CHICAGO, ILLINOIS, A CORPORATION OF VIRGINIA.

MILEAGE-PERIOD-INDICATING ODOMETER.

Application filed August 31, 1922. Serial No. 585,421.

To all whom it may concern:

Be it known that I, FREDERIK G. WHITTINGTON, a citizen of the United States, residing in Evanston, in the county of Cook 5 and the State of Illinois, have invented certain new and useful Improvements in Mileage-Period-Indicating Odometers, of which the following is a specification, reference being had to the accompanying drawings, 10 forming a part thereof.

The purpose of this invention is to provide an improved and simplified construction for causing the dial train of an odometer to operate an indicating device for giving 15 notice to the driver of the vehicle upon which the odometer is carried, of the expiration of various periods, for attention to be given to the different parts and functions of the vehicle, as for oiling or renewing the 20 various parts of the mechanism. It consists in the elements and features of construction shown and described as indicated in the claims.

In the drawings:

25 Figure 1 is a face view of an odometer equipped with mechanism embodying this invention.

Figure 2 is a similar face view with the face plate partly broken away to disclose the 30 period indicating elements of the mechanism.

Figure 3 is a side or lower edge elevation of the same with the case partly broken away to disclose the mechanism.

35 Figure 4 is a section at the line 4-4 on Figure 3.

Figure 5 is a section at the line 5-5 on Figure 4.

In the structure shown in the drawings, 40 the odometer is represented as comprising the customary trip train and total mileage train, the trip train dials being indicated at B, B¹ and B², the total mileage dial trains at A¹, A², A³, A⁴ and A⁵. α³ denotes the 45 carrying pinion from the hundreds dial wheel to the thousands dial wheel of the total mileage train, which therefore makes one step of rotation, that is communicates one digital step to the dial wheel which it 50 drives, for each 100 miles travel. Meshing with the continuous toothed zone of this pinion there is a spur gear, C, carried on a short shaft, c, which is journaled in an auxiliary gear supporting frame, M, herein-

after more particularly described, and which 55 has at its left hand end a miter-gear pinion, D, meshing with a miter gear pinion, E, the latter being fixed on a shaft, e, journaled in the same auxiliary frame, M, and carrying at its upper or forward end above the 60 upper or forward end of the upper or forward bar, M¹, of said frame, M, the initial period-indicating disk and gear, F. Journaled upon said frame bar, M¹, in the plane of said disk, F, are succeeding indicating 65 disks and gears, G and H, all of said disks, F, G and H, being in a plane substantially parallel with and immediately behind the dial plate, P, of the odometer. Said disk gears, F, G and H, are of the mutilated and 70 delay segment type adapted to communicate motion from each to the succeeding one, by steps only, as the gear tooth of each, passing the delay surface of the engaged gear, arrives at a tooth-recess with which it 75 engages for communicating the step movement throughout the arc of intersection of the pitch lines of the two gears, leaving the driven gear at rest while the driving gear continues its rotation throughout the arc of 80 its own delay surface. By means of this type of gear it will be seen that any desired reduction of speed may be made from each gear to the next in the series, without employing intermediate speed-changing gears 85 or two gears on the same shaft with a different number of teeth. The importance of this expedient for the present purpose is that it makes it possible with the minimum number of parts, to construct the series of 90 disks having successively reduced speed, so that they all stand in the same zone or plane immediately behind the sight openings of the face plate; and also that it avoids having the disks move gradually past the sight 95 openings, and causes, instead, that they stand at rest in the intervals between their consecutive step movements and perform those movements each in the time occupied by a single digital movement of the 100 odometer train, which according to the usual construction of odometers is made during ¹⁶ of a mile of travel.

The disks, F, G and H, have each an annular area subdivided into equal sectoral 105 units corresponding to the step movements of each disk; and the face plate has corresponding sectoral sight openings, f, g, and

h, through which the markings on the indicating disks, F, G and H, may be read. As indicated, the initial indicator disk, F, being driven by the gear connection described, with the pinion, a^3 , whose step movements corresponding to the digital step of the odometer train at each hundredth mile, the disk, F, makes a step movement at every hundredth mile. The gear, C, has five times as many teeth as the pinion, a^3 , and the miter gears, D and E, are equal, so that the disk, F, makes its revolution in five steps each corresponding to 100 miles travel. Its surface which is exposed at the sight opening, *g*, is therefore exposed in five sectoral sections successively in the course of its revolution. This disk is utilized for signaling the expiration of 500 mile periods and it has therefore one sector of 72° extent marked for reading through the sight opening and giving the desired signal. The disk, G, is toothed relatively to the disk, F, for making one revolution in each two revolutions of the disk, F, its step movement being 36° in extent and its revolution being made in ten 100 mile steps, making a full revolution in each 1000 miles travel. Its surface is divided into ten sectors, and it is utilized for signaling expiration of 200 mile periods, alternate sectors being therefore distinctively marked as hereinafter described. The third disk, H, is toothed relatively to the disk, G, for making the same in eight steps of 45° . This disk is utilized for signaling the expiration of 2000-mile and 4000-mile periods; and it has therefore two diametrically opposite sectors distinctively marked for reading as they come around to the sight opening, *h*.

The preferred marking for the various signals, that is for distinguishing the different sectors of the different disks as they successively appear at the sight openings is by color; that is the sectors to be read are distinctively colored. In order that each mileage at which a warning is to be given may have its own distinctive coloring, to the end that the appearance of a certain color marking shall always inform the driver of a certain duty,—of attention to a particular function or part of the mechanism,—and that the concurrent expiration of two different attention periods as a 200 mile period and a 1000 mile period, or a 2000 mile period and a 4000 mile period shall give him both color signals at the same place,—that is by the appearance of the same marked sector through the same opening, the following scheme of color marking is adopted:

In view of the fact that the several mileage periods at which warnings are to be given are 200 miles, 500 miles, 1000 miles, 2000 miles and 4000 miles, five colors are appropriated, preferably white, black, red, green and yellow, each of which is at all

times sharply distinguished from the others. The middle disk, G, making its rotation in ten steps of 100 miles each is divided into ten sectors and alternate sectors are colored for signaling, the other alternate sectors being left blank so that their appearance at the sight opening does not constitute a signal. Four of the five colored sectors are given a solid or unitary color, as white. The fifth sector is half white and half black. The driver's key chart will inform him that the color, "white," invariably indicates a certain attention to be given at 200 mile intervals; and that the color, "black," indicates a certain other attention to be given at 1000 mile intervals. When the fifth sector appears the driver reads, "white" and "black" and is thereby informed of both duties.

The third disk making its revolution in eight steps of 500 miles each, is appropriated to indicating 2000 mile and 4000 mile intervals, and therefore has two diametrically opposite 45° sectors colored,—one of them red only, the key chart informing the driver that "red" indicates a duty to be performed at 2000 mile intervals; the other, colored half red and half green, the key chart informing the driver that "green" indicates a duty to be performed at 4000 mile intervals. Whenever this two-color,—red and green,—sector appears, the driver is informed of both duties to be performed at once.

The first disk, F, making its revolution in five steps of 100 miles each, is devoted to giving the 500 mile signals and for that purpose has one sector of 72° colored yellow only.

I claim:—

1. In combination with an odometer a mileage period indicating device comprising a series of indicating disks mounted for step-by-step rotation parallel to the face plate of the odometer, said face plate having sight openings for disclosing aliquot parts of annular areas of the disks respectively, and means for imparting step-by-step rotation to said disks from the odometer train.

2. In the construction defined in claim 1 foregoing, said means comprising an operating train in which said disks are successively connected for said step-by-step rotation and gear means for actuating the initial disk of the series from the odometer dial train; whereby said initial disk has step-by-step rotation in steps corresponding to the digital steps of a selected one of the odometer dials.

3. In the construction defined in claim 1 foregoing, speed changing gear connections from disk to disk of said period indicating series comprising a mutilated gear with relay segments adapted for transmitting ro

tation to each gear from the preceding one of the series in steps only; whereby the duration of each step movement of all of the disks is the duration of that of the initial movement, and each step movement of the final disk is coincident with a step movement of all preceding disks.

4. In the construction defined in claim 1 foregoing, the disks having sectoral areas circumferentially distributed for registering with the sight openings at the limit of the step movements of the disk, said areas being distinguished from each other by different surface markings on them respectively.

5. In the construction defined in claim 1 foregoing, the disks having sectoral areas circumferentially distributed for registering with the sight openings at the limit of the step movements of the disks, certain of said areas being distinguished from others by different color markings on their surfaces respectively.

6. In the construction defined in claim 1 foregoing, the disks having sectoral areas circumferentially distributed for registering with the sight openings at the limit of the step movements of the disks, said areas being distinguished from each other by different color markings of their surfaces respectively, said color markings comprising a plurality of colors employed at certain sectors singly,—that is so that only one color appears at each exposed area, and comprising also the several colors in different combinations by twos,—that is so that two colors appear at the exposed area; whereby the number of distinguishable color markings is the total of the number of colors employed

plus the number of their possible different combinations by twos.

7. In the construction defined in claim 1 foregoing, the gear connection from disk to disk being by mutilated and delay segment gears, whereby the step movements of all the disks, however variant and angular in extent, are each completed in a single continuous impulse which is coincident with and as long as a digital step of the initial dial of the odometer train.

8. In the construction defined in claim 1 foregoing, the gear connection for actuating the initial disk being made by a gear element of the odometer train whose step movements are made at 100 mile intervals, whereby the minimum duration of exposure of any disk marking is throughout 100 miles of travel.

9. In the construction defined in claim 1 foregoing, the disks having sectoral areas circumferentially distributed for registering with the sight openings at the limits of the step movements of the disks respectively, said areas being distinguished from each other by different color markings of their surfaces respectively, a separate color being appropriated for each mileage period at which warning is to be given, sectoral areas which in the order of rotation of the disks appear at the concurrent expiration of two different mileage periods bearing the two colors appropriated for such periods respectively.

In testimony whereof, I have hereunto set my hand at Chicago, Illinois, this 28 day of August, 1922.

FREDERIK G. WHITTINGTON.
